WILLIAM B. CROWELL, OF NEW YORK, N. Y.

CHECKING MEANS FOR DOOR-OPERATING MECHANISM.

Application filed June 21, 1923. Serial No. 646,779.

The present invention relates to a door-operating mechanism, and more particularly to mechanism in which cushioning action is attained in the movements thereof.

5 In the operation of doors, it is essential that the closing movement of the door be attained with a yieldable force and with a speed such that the momentum attained by the door will not be sufficient to close the 10 door against objects which may be in its path. In the opening of the door, however, there is little danger to passengers in rapid movement of the door and cushioning means may be employed for cushioning the opening 15 movement of the door which might not be suitable in closing movements thereof but which are particularly adapted to attain a positive and rapid cushioning action. The present invention aims to provide yieldable 20 cushioning means in the closing movement of doors and the like, and a more positive delaying action such as may be obtained by the use of liquids in cushioning devices in the opening movement of the door.

25 The primary object of the present invention is to provide a door operating mechanism having cushioning means operating with a liquid for the opening movement of the door.

30 Another object of the invention is to provide a door operating mechanism in which the movement of the door will be rapid, and which will not be retarded by cushioning means before approaching the end of the 35 stroke.

A further object of the invention is to provide a mechanism for operating doors and similar devices which shall be simple in 40 operation and in which the parts of the mechanism are readily accessible to be easily regulated, and which may be maintained in operating condition with a minimum of care and attention.

With these and various other objects in 45 view, the invention comprises the various features hereinafter claimed and fully described in connection with the accompanying drawings, in which—

50 Fig. 1 is a sectional view of a device embodying the features of the invention showing the control valve in position for admission of pressure fluid;

55 Fig. 2 is a detail view of a section of the device showing the operating valve in position for exhaust of pressure fluid from the cylinder;

Fig. 3 is a view of the device embodying the invention showing the manner of attachment in operative position to the toggle lever of an elevator door mechanism. 60

The preferred form of the invention comprises a cylindrical casing 12 having an upper head 14 and a lower head 16 which may be attached to the casing by screw-threaded connections 18 and 20. Within the casing 12 65 is a piston 22 to which a piston rod 24 is connected, which passes upwardly through an opening 26 in the upper cylinder head 14 and through a partition 28 in the cylinder having a central opening 30 therein. Surrounding the piston rod 24 and between the partition 28 and piston 22 is a helical spring 32 which may be seated at one end on a flanged portion 23 of the piston 22 and held in place at the other end by means of a circular projection 29 on a partition 28. The spring is adjusted in position so as to be under tension and serve to return the piston to the lower end of the cylinder after operation of the piston by means of pressure fluid. 70 Means are provided for admitting air or other pressure fluid below the piston 22 through a port 42 in the cylinder head 16, the pressure fluid being admitted from a pipe 34 attached to the cylinder head 16, 75 through a valve casing 36 which may be formed integral, if desired, with the cylinder head 16. In the valve casing 36 is a valve 38 having a passageway or port 40 therein for admission of pressure fluid. 80 When the valve 38 is turned so that the port 40 registers with the pipe 34 and with the port 42, pressure fluid is admitted to the cylinder. In the valve 38 is a second passageway or port 39 which is preferably 85 smaller than the port or passageway 40 and which leads from the central portion of the passageway 40 radially outwardly to the exterior of the valve. At a suitable point in the valve casing 36 is a port opening 41 with which the passage 40 registers when the valve is turned so that the passage 39 registers with the port 42 to permit exhaust from the cylinder. Attached to the port 41 is a regulating screw 44 having a restricted 90 opening therein by means of which exhaust through the port opening 41 may be controlled and thus provide any desired amount of cushioning action in the return stroke of the piston. 95

The piston 22 may be provided with a leather cup or washer 46 held in place by 100

means of a ring 47. By means of the leather washer a smooth sliding action between the cylinder and piston is attained and leakage of fluid between the cylinder wall and the piston is thereby prevented.

In order to provide for cushioning action during the forward movement of the piston corresponding to the opening of the door, I provide a cup and plunger operating with a liquid to check the forward or upward stroke of the piston without causing jar or noise. The cushioning means comprises a cup plunger or hollow piston 48 which is attached to the piston rod 24 by any suitable means such, for example, as a pin passing through a slot in the piston rod and a corresponding slot in a projecting member 49 in the base of the cup plunger. Cooperating with the cup plunger 48 is a stationary hollow plunger 50 having a neck portion 51 which may be attached to the head 14 by screw-thread connections 27 in the opening 26 in the head. In order to prevent leakage of oil around the piston rod 24 and the hollow plunger 50, I provide suitable packing 52 held in place in the neck portion 51 of the plunger by means of a cup or collar 54 which is attached to the neck portion preferably by screw-thread connections 53.

In the lower end of the cup plunger is a base preferably comprising two parts 56 and 58 which may be attached to the plunger walls by means of screw-thread connections. In the base portion 56 are passages 57 and 59 which communicate through the space between the base portions with a passageway 61 in the upper base member 58. In order to regulate passage of liquid through the passageways when the cup plunger 48 moves upward so as to envelop the stationary plunger 50, I provide a regulating screw 62 which is adapted to pass through an opening 63 in the head 14 and an opening 64 in the top of the plunger casting 50. The regulating screw may be maintained at any desired position or setting by means of a lock nut 66 above the head 14. In the side walls of the plunger 50 above the base portions 56 and 58 are passages 65 and 67 through which oil may freely pass when the cup plunger moves downwardly away from the hollow plunger 50 whereby retardation in the downward movement of the piston by the checking action is prevented.

In order to attain proper cushioning action in the movements of the piston and the parts operatively connected thereto, a liquid such as oil or glycerine is maintained in the cup plunger and by properly adjusting the screw 62 the passage of liquid through the various passages may be controlled and any desired amount of cushioning action thereby attained. Any suitable means may be provided for placing liquid in the plunger such,

for example, as an opening 68 which may be closed by means of a plug or stopper 70.

In order to prevent leakage of oil or other liquid between the cylinder head 14 and the cylinder casing 12, I provide a packing 72 held in place by means of a screw-threaded ring 74 which is adjustable in position on the screw-threaded portion 18 of the cylinder. Packing may also be provided around the piston rod between the base portions 56 and 58 as shown in Fig. 1.

In the operation of the device as applied, for example, to the usual hand operating levers 4 of an elevator door 5, the device may be supported by means of a suitable bracket 2 attached to the elevator hatchway, and may be connected to the toggle lever through a lug 3 attached to the piston rod 24 and to the said lever. The elevator door is supported as shown in the drawing, on an overhead track 6 in the ordinary manner. When it is desired to open the elevator door, pressure fluid is admitted to the cylinder casing by turning the valve 38 in position for admission, as shown in Fig. 1 of the drawings. Pressure fluid enters the cylinder through the port 42 and forces the piston 22 upwardly against the tension of the spring 32. The plunger 48 attached to the piston rod 24 moves upwardly with the movement of the piston and engages the hollow plunger 50. The oil in the plunger 48 is forced into passages 57-59 and through the passage 61 controlled by the regulating screw 62. After the plunger 48 has moved into a position so as to cover the ports 65 and 67, the liquid in the plunger 48 passes into the interior of the hollow plunger 50 and compresses the air therein, thus assisting in the cushioning action. By means of the cushioning device 48-50 operating with the liquid, a strongly retarding action is attained for the opening movement of the door.

As long as the pressure fluid is operating upon the piston 22, the elevator door remains in open position. When it is desired to close the door, the valve 38 is turned so that the port or passage 39 registers with the port 42 and the passageway 40 registers with the opening 41 controlled by regulating screw 44. In this position exhaust takes place from the cylinder through port 42, passage 39, passage 40 and through the regulating screw 44 to the atmosphere. In a downward or return movement of the piston, the plunger 48 moves downwardly from the plunger 50 uncovering the ports 65 and 67. As soon as the ports are uncovered, oil flows from the interior of the plunger 50 through the ports around the external portion of the plunger 50, and oil may then flow back into the plunger 48 without passing through the restricted passage 61 and passages 57-59 to the plunger. In the return movement of

the piston 22, the air or other operating fluid below the piston is compressed due to the gradual exhaust through the restricted regulating screw 44. The pressure fluid 5 serves therefore to attain cushioning action in the return movement of the piston.

It is to be understood that the form of the invention which has been described constitutes the preferred form thereof, but that 10 various changes and modifications may be made in the device without departing from the spirit or scope of the invention as defined in the claims.

Having thus described the invention, what 15 is claimed as new is:

1. In a mechanism for controlling the movement of a door, a liquid containing chamber, a vertically disposed liquid holding vessel forming a confining wall for said 20 chamber, a motion imparting member connecting said vessel to said door whereby movement of said door in one direction causes upward travel of said vessel, and means in said chamber tending to impede 25 the last portion of the upward travel of said vessel, said means being inoperative during the initial portion of the travel of said vessel in the upward direction.
2. In a mechanism for controlling the 30 movement of a door, a liquid containing chamber, a vertically disposed fluid holding cup forming a confining wall for said chamber, a motion imparting member connecting said cup to said door whereby movement of 35 said door in one direction causes upward

travel of said cup, means tending to impede the last portion of the upward travel of said cup comprising a stationary member spaced from said cup when the latter is at the bottom of the said chamber and adapted to be 40 surrounded by the cup when the latter approaches the end of its upward travel whereby the last portion only of the upward stroke of the cup is impeded.

3. In a mechanism for controlling the 45 movement of a door, means for retarding the last portion of the door's travel in one direction comprising a liquid containing chamber, a vertically disposed liquid holding vessel forming a confining wall for said 50 chamber, a motion imparting member connecting said vessel to said door whereby movement of said door in one direction causes upward travel of said vessel, means tending to impede the last portion of the 55 upward travel of said vessel comprising a stationary member enveloped by said vessel only when the latter approaches the end of its upward travel, a passage through said stationary member permitting the gradual 60 escape of liquid confined in said vessel as the upward travel of said vessel brings the liquid into contact with said stationary member, and means for varying the free area of 65 said passage comprising an adjustable valve member extending into said stationary member.

Signed at New York city, N. Y., this 19th day of June, 1923.

WILLIAM B. CROWELL.
